Primary Examiner — John A Voytek(74) *Attorney, Agent, or Firm* — Dickinson Wright PLLC(57) **CLAIM**

The ornamental design for a tire, as shown and described.

DESCRIPTION

FIG. 1 is a perspective view of the tire of my design; FIG. 2 is a front elevation view of the tire of my design; FIG. 3 is a side elevation view of the tire of my design; and, FIG. 4 is a side elevation view of the tire of my design, taken from the opposite side of that shown in FIG. 3.

The dash-dot-dot-dash lines define the boundaries of the claim. The broken line disclosure in the drawings depicts environmental subject matter forming no part of the claimed design.
